(57) **CLAIM**

The ornamental design for a bracket, as shown and described.

DESCRIPTION

FIG. 1 is a rear-bottom-right perspective view of a bracket according to the claimed design.

FIG. 2 is a rear-top-left perspective view of the bracket.

FIG. 3 is a front-bottom-right view of the bracket.

FIG. 4 is a front-top-left perspective view of the bracket.

FIG. 5 is a rear view of the bracket.

FIG. 6 is a front view of the bracket.

FIG. 7 is a bottom view of the bracket.

FIG. 8 is a top view of the bracket.

FIG. 9 is a right side view of the bracket.

FIG. 10 is a left side view of the bracket; and,

FIG. 11 is a rear-bottom-right sectional perspective view of the bracket taken along line 11-11 in FIG. 7.

The dash-dash broken lines in the drawings illustrate portions of the bracket that form no part of the claimed design. The dash-dot-dash broken lines in the drawings define the bounds of the claimed design and form no part thereof.

The dash-dot-dot sectional broken lines in FIG. 7 form no part of the claimed design.

The oblique broken-line hatch shading in FIG. 11 illustrates interior portions of the bracket that form no part of the claimed design.
